John W. Burt

Des. 1625

John W. Burt, of New York, N.Y.
Letters Patent No. 1625, dated Aug. 12, 1862,

The schedule referred to in these Letters Patent and making part of the same.

To all whom it may concern:

Be it known that I, J. W. Burt, of the City County and State of New York, have produced a new and ornamental design for Anklet; and I do hereby declare that the following is a full, clear and exact description of the same, reference being had to the accompanying drawing forming part of this specification, in which

Figure 1, is a plan view of my anklet when the same is spread out flat.

Figure 2, is a side elevation of the same, attached to a leg.

Dec 1625

Similar letters of reference in both views indicate corresponding parts.

My design consists principally in cutting the edges of the anklet each with five points, two at the ends, and three in the centre, in such a manner that when the anklet is attached to a leg the points at the ends join and form a point similar to the points in the middle, and the whole assumes a neat and becoming appearance.

To enable those skilled in the art to make and use my design I will proceed to describe it with reference to the drawing.

The anklet A. is cut out of a piece of enamelled or patent leather or of any other suitable material, so that when the ends of the same are brought together it forms a conical frustum which will fit to the leg of a person, above the boot or gaiter.

The upper edge of this anklet is provided with five points a, a', three points a, in the middle, and two a', at the ends, said points being at equal distances apart or nearly so, and separated from each other by semi circular wave lines 3. The points a', at the ends are sharper than those in the middle and each of them forms an angle of about 15 degrees, whereas the angle of the points a, is 90 degrees or nearly so, so that when by joining the ends of the anklet the two points a' are brought together, a point a² is formed (see Figure 2) equal to the points a,

The lower edge of the anklet is ornamented with the same number of points c, c', as the upper edge, and these points are separated by similar semi circular wave lines 2, said points and wave lines however are smaller in proportion than the points a, a', and wave lines 3, as clearly shown in Figure 1. of the drawing.

The ends of the anklet are provided with a number of eyelets e, of brass or other bright material which shows well on the dark surface of the anklet, and these eyelets serve to receive the lacing which extends up from the boot or gaiter as shown in Figure 2, whereby the appearance of the whole is rendered pleasing to the eye and uniform, and at the same time the anklet is prevented turning on the leg, which would materially impair its good appearance.

Dec. 1625

Having thus described my design, what I claim as new and desire to secure by Letters Patent, is -

The anklet having points a. a', at the upper, and points c. c', at the lower edge, and fastened by a lacing extending up from the boot or gauntlet through eyelets v, as shown and described.
